ABSTRACT

A template and method of marking a person's face. A formable sheet of plastic is placed onto a person's face in a heated condition and forced against the face to assume the face shape. A plurality of small circles are marked onto the formed sheet to define the various facial contour features. The sheet is then removed from the face and openings are created in the sheet along the contour lines. The sheet has an elastic band mounted thereon for subsequent remounting to the person's face. A marker is extended through the various openings against the face marking the contour lines created in the template onto the face.

TEMPLATE

CROSS REFERENCE TO RELATED APPLICATION

This application is a continuation-in-part of my co-pending U.S. Pat. application Ser. No. 154,232 filed Feb. 10, 1988 and entitled Cosmetic Template, now U.S. Pat. No. 4,886,079 issued Dec. 12, 1989.

BACKGROUND OF THE INVENTION

This invention is in the field of devices utilized in the application of cosmetics to a person's face. Exceptional skill obtained through years of practice and training is required to correctly apply cosmetics to a person's face. Professional beauticians are able to correctly locate and apply cosmetics on a person's face as well as achieve the desired color and shading to create the desired illusion. Non-professionals may encounter difficulty in achieving the same result, particularly when the cosmetics are to be applied to the face of the same person applying the cosmetics.

I have therefore designed a cosmetic template initially created by the beautician thereby providing a cosmetic guideline to be followed to achieve the desired shading and location. The template may be readily used at home on multiple occasions without further need to consult with the beautician.

Various stencils have been previously provided for the application of cosmetics. For example, U.S. Pat. No. 2,931,369, issued to Badovinac, discloses a stencil for the application of lipstick, whereas U.S. Pat. No. 3,557,805, issued to Hamada, discloses a guide to create a variety of different eyebrow shapes. Another eyebrow guide is disclosed in U.S. Pat. No. 2,628,626, issued to Teillaud. Facial masks are also known such as a theatrical face mask disclosed in U.S. Pat. No. 4,397,701, issued to Johnson, et al., as well as a beauty mask disclosed in U.S. Pat. No. 2,671,446, issued to Mann. The latter mask is worn over an extended period of time for the eradication of wrinkles and for reshaping of facial muscles.

It has not heretofore been known to provide a facial mask initially created by a professional applicator of cosmetics and then utilized at home without further consultation.

Further, the present invention may be used in the medical field wherein it is necessary to orient x-ray machines in the same position relative to a patient's face and/or mark a patient's face to facilitate the repetitive application of surgical techniques. It is the current practice in the medical surgery field to fixedly fasten the patient to a supporting surface by bolts or other means in order to insure that the patient is in the same position and orientation as in a prior medical visit. Such procedure is inaccurate, uncomfortable and time consuming. Disclosed herein is a template and method which in certain instances will completely alleviate the necessity for such a fastening procedure.

SUMMARY OF THE INVENTION

One embodiment of the present invention is a method of applying marks to a person's face comprising the steps of heating a flexible sheet of plastic to a heated condition, placing the sheet in the heated condition 65 against a person's face, forcing the sheet to assume a shape corresponding to various contours of the person's face creating areas to be marked, marking the areas on

the sheet, removing the sheet from the person's face, removing various portions from the sheet according to the markings creating a plurality of openings in the sheet, placing the sheet against the person's face, marking through the openings the person's face.

It is an object of the present invention to provide a template for marking a person's face.

In addition, it is an object of the present invention to provide a new and improved method of marking a person's face.

Related objects and advantages of the present invention will be apparent from the following description.

BRIEF DESCRIPTION OF THE DRAWING

FIG. 1 is a plan view of an unformed sheet to be used with the instant invention.

FIG. 2 is the same view as FIG. 1 only showing the sheet formed to its final shape.

FIG. 3 is a side view of the template of FIG. 2 being placed adjacent a person's face.

FIG. 4 is a fragmentary enlarged cross-sectional view taken along line 4—4 of FIG. 3 and viewed in the direction of the arrows.

DESCRIPTION OF THE PREFERRED EMBODIMENT

For the purposes of promoting an understanding of the principles of the invention, reference will now be made to the embodiment illustrated in the drawing and specific language will be used to describe the same. It will nevertheless be understood that no limitation of the scope of the invention is thereby intended, such alterations and further modifications in the illustrated device, and such further applications of the principles of the invention as illustrated therein being contemplated as would normally occur to one skilled in the art to which the invention relates.

Referring now more particularly to the drawing, there is shown the cosmetic template 10 (FIG. 3) for mounting to a person's face 11 for applying cosmetic guidelines to be used in the application of cosmetics. Template 10 is formed from a flat sheet 12 which is then heated and forced against the face to assume the same shape as the face. Markings are made for shading, illusion and contouring with permanent marking pencils of various colors to further guide the person in color and application of make-up. The template is removed from the face and a plurality of openings are formed in sheet 12 to allow cosmetic guidelines to be marked through the openings onto the face. The template is then removed and the cosmetics are applied in accordance with the cosmetic guidelines marked on the face.

Sheet 12 is produced from a clear plastic material that is non-toxic and safe to the skin. Most importantly the sheet must have a relatively low melting point of between 120° and 160° F. so that it can be shaped and molded by hand, and then hardened to the final shape. Best results have been obtained by producing the sheet 60 from an extrude plastic material such as polyester having a thickness of between 0.010 to 0.030 inches. One such material which is suitable for use is available in extruded sheets of polyester having a thickness of between 0.100 inches and 0.015 inches.

In order to form the template, a pair of breathing holes 13 and 14 are formed in the sheet with the sheet then being mounted into a frame extending circumferentially around the sheet preventing wrinkles and al-

lowing the sheet to be handled with a sufficient amount of control and flexibility. The frame may consist of strips of tape 15 and 16 which extend on the opposite sides and periphery of the sheet. Thus, as shown in FIGS. 3 and 4, strip 15 of tape extends around the circumference of the sheet. With the other strip 16 being positioned on the opposite side thereof. The sheet is then dipped in hot water having a temperature of approximately 200° to 240° F. and immediately placed over and in contact with the person's face with care being exercised to align apertures 13 and 14 with the nostrils. The sheet is then forced to assume a shape corresponding to the various contours of face 11 by simply applying fingers against the sheet and forcing the sheet into the various peaks and valleys, and other contours of the face. The mask is then left on the face to cool and permanently set the assumed shape into the sheet.

Sheet 12 is marked with the various contour lines and points once the sheet has hardened to its final set shape. For example, circles may be drawn or marked at the bottom of the sheet to form the chin contour line 17 as well as the lip line 18. Further, cheek contour lines 19 and eyebrow lines 20 are formed by drawing or marking similar circles onto the sheet while it is adjacent face 11. The nose contour lines 21 are formed by marking circles onto the sheet on the opposite sides of the nose and blush areas 22 and 23 are formed by marking circles forming the cheek contour lines 19 on the sheet. A pair of openings 24 and 25 are marked on the sheet following the outline of the person's eyes. Shadow shade areas 26 and 27 adjacent the eyes are indicated by marking a plurality of circles 28 extending rearwardly from the eyes.

The marked sheet is removed from the person's face. The sheet is next cut to remove portions therefrom creating eyeholes 24 and 25. The various small circles shown in FIG. 2 and defining the chin contour line 17, lip line 18, cheek contour lines 19, nose contour lines 21 and eyebrow lines 20, along with any additional small circles marked onto the sheet are individually heated to melt the plastic material therefrom. For example, a heated pointed object such as a rod is extended through each of the circles defining the chin contour line thereby melting the plastic material within each small circle. The circles marked onto the sheet have an approximate diameter of 1/16th to 1/8th inch.

An elastic band 30 has a pair of opposite ends fixedly attached to each edge of the sheet approximately located adjacent each eye. The mask may then be removably mounted to a person's face. Further, a pair of self-adhesive hole reinforcement labels 31 and 32 may be mounted to the sheet surrounding holes 13 and 14 to add further rigidity to the material surrounding the breathing holes. Such labels are commercially available such as those used to reinforce paper surrounding a hole in looseleaf paper and are available from any office supply store.

Once the template is completely formed, marked and the various portions within the marked circles removed from the sheet, the template is ready to be used for the application of cosmetics to a person's face. Thus, the template is repositioned adjacent face 11 and a cosmetic pencil or other means is extended through each hole marking the face and defining the various contour lines or cosmetic guidelines on the face. The template is then removed from the face with the various contour guide lines on the face allowing the person to then apply the

cosmetics according to the various lines marked thereon.

The cosmetic template and method disclosed herein has many advantages as compared to the prior means for application of cosmetics. The chief advantage is that the template is originally formed by a professionally trained beautician who will not only shape the template to the person's face, but also mark the various contour lines thereon and remove the portions from the template defining the contour lines. The template may then be given to the person who may repeatedly use the template at home to mark on her face the various cosmetic guidelines simply by inserting a cosmetic pencil through the various openings thereby marking the face in accordance with the beautician's prior study. The user may then remove the template and apply the cosmetics in accordance with the cosmetic guidelines already marked on the face. That is, cosmetics may be applied along each line or between a set of lines depending upon the beautician's instructions.

Many variations in the present invention are contemplated and included herein. For example, the template and the method of producing the template may be used in the medical field. In such a case, the template may be positioned on the patient's face for repetitive application of x-rays and/or surgical techniques. For example, a dentist may have a need to take an x-ray photo of a specific area of the patient's face to compare it with an identical x-ray photo taken previously. The previous photo may have been taken prior to surgery whereas the latter photo is to be taken after surgery. Thus, it is necessary to orient the x-ray machine in the same position relative to the patient's face. The same template utilized in marking the face prior to taking the first x-ray to orient the x-ray machine may be utilized to mark the face prior to orienting the x-ray machine before taking the second x-ray. A similar need exists in the plastic surgery field wherein the physician on multiple occasions needs to mark the patient's face to allow comparison from initial to final visits in order to arrive at the final facial contour. Additional uses of the template and method disclosed herein would be in the field of entertainment by make-up artists, and for such specific uses as for clowns and in the application of tattoos.

While the invention has been illustrated and described in detail in the drawings and foregoing description, the same is to be considered as illustrative and not restrictive in character, it being understood that only the preferred embodiment has been shown and described and that all changes and modifications that come within the spirit of the invention are desired to be protected.

What is claimed is:

1. A method comprising the steps of:
heating a thin flexible sheet of plastic to a heated condition;
placing said sheet in said heated condition against a person's face;
forcing said sheet while on the person's face and in said heated condition to assume a shape corresponding to various contours of the person's face creating areas to be marked;
marking said areas on said sheet; and,
removing various portions from said sheet according to said marking creating a plurality of openings in said sheet.

2. The method of claim 1 and further comprising:
forming breathing holes in said sheet; and,

leaving said sheet on the person's face to cool and assume a fixed contour while on the person's face.

3. A method comprising the steps of:

heating a flexible sheet of plastic to a heated condition; 5

placing said sheet in said heated condition against a person's face;

forcing said sheet to assume a shape corresponding to various contours of the person's face creating areas 10 to be marked;

marking said areas on said sheet;

removing various portions from said sheet according to said marking creating a plurality of openings in 15 said sheet;

forming breathing holes in said sheet;

leaving said sheet on the person's face to cool and assume a fixed contour; and, 20

marking guide indicia through said openings onto the person's face.

4. The method of claim 3 and further comprising:

mounting eyelets around said breathing holes;

cooling said sheet after said shape is created to fix said 25 shape in said sheet; and,

melting said sheet at said markings to remove said various portions from said sheet.

5. The method of claim 4 and further comprising: 30

said placing of said sheet in a heated condition includes inserting said sheet into water having a temperature in excess of 200° F.

6. A method comprising the steps of: 35

heating a flexible sheet of plastic to a heated condition;

placing said sheet in said heated condition against a person's face;

forcing said sheet to assume a shape corresponding to various contours of the person's face creating areas to be marked;

marking said areas on said sheet;

removing various portions from said sheet according to said marking creating a plurality of openings in 10 said sheet;

forming breathing holes in said sheet;

leaving said sheet on the person's face to cool and assume a fixed contour;

marking guide indicia through said openings onto the person's face;

taking a first x-ray photo at the location of said guide indicia;

placing said sheet on the person's face; and

taking a second x-ray photo at said location.

7. A method comprising the steps of:

heating a flexible sheet of plastic to a heated condition;

placing said sheet in said heated condition against a person's face;

forcing said sheet to assume a shape corresponding to various contours of the person's face creating areas 20 to be marked;

marking said areas on said sheet;

removing various portions from said sheet according to said marking creating a plurality of openings in 25 said sheet;

forming breathing holes in said sheet;

leaving said sheet on the person's face to cool and assume a fixed contour;

marking guide indicia through said openings onto the person's face;

performing a medical step at the location of said 30 guide indicia;

placing said sheet on the person's face; and

performing a second medical step at the location of said guide indicia.
